GARMENT

Filed July 11, 1928

UNITED STATES PATENT OFFICE

GEORGE H. FRANCISCO, OF LOS ANGELES, CALIFORNIA, ASSIGNOR OF ONE-HALF TO
ANNIE A. DAVIS, OF LOS ANGELES, CALIFORNIA

GARMENT

Application filed July 11, 1928. Serial No. 291,751.

This application is in part a continuation of my copending application filed on May 18, 1928, under Ser. No. 278,680, and takes the place of said application while preserving to 5 applicant the filing date on duplicate matter shown and claimed.

This invention relates to garments, such as overalls, bathing suits, under garments, and in fact garments generally which are retained 10 in position on the wearer by means of straps or suspenders passing over the shoulders.

The objects of the invention are to provide 15 improvements in the shoulder straps or suspender arrangement which will greatly facilitate putting on or taking off such garments and which will overcome the tendency of the buttoned ends of such straps from becoming disarranged or twisted in putting on the garment.

20 Before describing the improvements attention is drawn to the common construction of such garments wherein the shoulder straps are permanently sewed to the garment, as for instance in a bathing suit or pair of ordinary 25 overalls.

In a bathing suit both of the straps are sewed to the rear of the garment and pass over the shoulders to button in front of the shoulder.

30 Overalls are frequently constructed in the same manner as the bathing suit as far as the shoulder straps are concerned, but are often provided with buckles for adjusting the length of the straps, and sometimes the straps 35 include rubber like a pair of suspenders and are detachable or buttoned to the garment at the ends like any pair of suspenders so that they may be removed when washing the garment and thus prevent injury to the rubber.

40 In the case of overalls, especially those which come up high on the body, or which have a high bib in front, it is necessary to unbutton at least one of the shoulder straps in front so that the other can be slipped off 45 of the shoulder and the garment removed. The same applies to bathing suits or undergarments provided with shoulder straps (omitting those which are woven in a manner to stretch over the head like a sweater).

50 In any event, in putting on a garment with

one or both straps unbuttoned in front, the strap or straps hang down in back and are awkwardly reached for bringing over the shoulder to button in front, hence it is common practice for a mechanic in removing his 55 overalls to unbutton only one of the straps in front and slip the other off without unbuttoning, but when this is done the unbuttoned strap again hangs down the back when donning the garment, and besides this the buttoned strap may become twisted on the button. This latter difficulty occurs chiefly with 60 such straps as are provided with linked wire loops for attaching to the buttons as in mechanics' overall construction. 65

My invention hereinafter described in detail, is applicable to any such garments as are held up with shoulder straps whether the straps are permanently sewed at all ends to the garment, or constructed to unbutton at 70 one or both ends in front, or unbutton at all ends, but in any case in order to remove the garment it is only necessary to release one button or a front flap of the garment to permit the straps to be slipped off of the shoulders, 75 the strap to be slipped off first being of special construction provided with a long front extension passing downward and securing to a lower part of the garment either by buttoning or sewing, so that when again putting on 80 the garment no free end of a strap will hang down the back to be groped for but the garment will go in place much like a pair of pants with suspenders buttoned at both ends, except that the shorter strap will first be 85 slipped over a shoulder, then the strap with the extension, and after which the flap (or bib in the case of overalls) will button to the special strap to hold both from spreading.

In the drawings forming part of this application Fig. 1 shows a bathing suit or shirt constructed in accordance with my invention, and shows the invention in its simplest form.

Fig. 2 shows the garment of Fig. 1 unbuttoned disclosing the special or extended shoulder strap.

Fig. 3 is a perspective view of a pair of bib overalls provided with my improved straps with all ends sewed permanently to the garment.

Fig. 4 is a view similar to that of Fig. 3 showing a bib overall but shows all ends of the straps buttoned or detachable from the garment to facilitate washing.

Fig. 5 is an enlarged view of the corner of the bib showing the strap buttoned thereto and the means which prevents displacement or twisting of the eye, buttonhole, or loop on the button.

Fig. 6 is an enlarged side view of a portion of the special strap to more clearly show the detachable extension.

In further detail in Figs. 1 and 2 the body of the garment is indicated at 1, shoulder straps 2, 3 and front flap 4.

The strap 2 is of ordinary construction and may or may not be buttoned as desired, though here it is shown as a permanent non-detachable part of the garment.

The garment is split down one side to form a flap 4, and strap 3 instead of terminating at the shoulder for buttoning to the garment as is customary, is provided with a long extension 3' passing downward and sewed or otherwise secured to the garment at 5 adjacent the bottom end of the slit or parting which forms the flap.

This special strap is provided with a button 6 which buttons to a buttonhole 7 in the flap, and preferably a second button 8 on the strap buttons to a second buttonhole 9 on the flap.

When the garment is buttoned as shown in Fig. 1 the straps are held in place on the shoulders, but when the flap is unbuttoned from the strap as in Fig. 2 it will be readily seen that the strap 3 by reason of its extension and great length may easily be slipped off of the shoulder without releasing either of its ends from the garment, also that when strap 3 is slipped from the shoulder the other strap may also be slipped off and the garment removed.

Conversely when putting on the garment strap 2 is first placed over the shoulder, then strap 3, followed by buttoning the flap to the strap. The extension 3' of the strap keeps the strap in proper place so that it cannot become twisted like an unbuttoned strap and besides does away entirely with a loose strap hanging down the back which must be groped for in donning the garment.

In Fig. 3 the invention is shown applied to a mechanic's overalls of the bib type, the body of the garment being designated 10, the bib 11, and the two straps numbered 2 and 3 and extension 3' the same as in Figs. 1 and 2 to establish identity of features therewith. Buttons 6, 8 and holes 7, 9 are also shown, the only difference in the showing being the length-adjusting buckles 12 on the straps.

In Figs. 4, 5 and 6 the invention is shown applied to a pair of bib overalls and wherein the straps take the form of a pair of detachable suspenders, and other features are in-

corporated, this being the most complete form of the invention.

The body of the garment is designated 13, bib (or flap) 14, straps correspondingly to the other figures 2, 3, 3' and likewise buttons and holes 23, 24, also 18 and loop 17, and adjusting buckles 12.

In the straps of Fig. 4 rubber is incorporated at 15 and the rear ends are detachably buttoned to the garment at 16 in the common well known manner.

The forward ends of the straps are provided with eyes or hinged wire loops 17, 19 adapted to button respectively over buttons 18, 20.

On the corner of the bib at 21 is a tape or strap of material securely sewed at its ends to the bib and passing over and outside of the wire loop 19 which buttons to button 20. This strap functions to prevent the loop or eye 19 of the strap from swinging around or becoming twisted with respect to this button and insures that whenever the garment is picked up (with loop 19 engaging button 20) the garment will hang fair from the strap connection and cannot go wrong in slipping the strap over the shoulder.

The extension 3' of strap 3 is shown detachable from the main portion or strap 3 at a point adjacent the button loop 17. The construction by which it is made detachable may be of various forms, such for instance as a plain hook, though in the drawing I show it as extended through an extra loop 17' formed on the wire device 17 and buttoned upon itself, preferably by means of a snap fastener 22 all as clearly shown in Fig. 6.

In Fig. 4 the lower end of strap extension 3' is indicated as sewed or otherwise permanently secured to the garment as there is no need to disconnect it at this end for the purpose of removing the suspender elements when washing the garment, though it is manifest without additional drawings that the extension 3' may be buttoned or otherwise be made detachable at its lower end and in which case it need not be detachable at its upper end from the main portion 3 of the strap.

When the garment of Fig. 4 is buttoned the bib 14 functions precisely as the flap of Figs. 1 and 2 in holding the straps in proper place and preventing them from spreading apart and coming off of the shoulders.

In case of men's overalls subject to hard usage I preferably provide additional buttons and holes at each side as at 23, 24 where the bib is parted or slit down from the sides.

It is evident from the disclosure, that while I show the extension strap 3' at one side of the garment only, since it is not necessary to have one at both sides as the shorter strap can readily be slipped off upon releasing the edge of the flap buttoned to strap 3, 3', still if desired both sides may be constructed alike.

In the following claims the word "bib" is

intended to cover any such portion of a garment as the piece 4 of Fig. 1 or the bib 14 of Fig. 4 as they are equivalent in respect to this invention.

5 Also the words "attached" or "secured" are intended to cover any securing or integral attachment of the ends of the straps to the garment or equivalent detachable securing means used for the purpose intended.

10 I claim:

1. In a garment of the character described, a shoulder strap provided with means at its end whereby it is detachably connected to the garment, and a band secured at opposite ends 15 to the garment passing freely across the connecting end of said strap.

2. In a garment of the character described, a shoulder strap, a button loop suspended from said strap, a button on the margin of 20 the garment adapted to be engaged by said loop, and a band secured at opposite ends to said garment passing freely across said loop when engaged with said button.

3. In a garment of the character described, 25 a shoulder strap, a loop suspended from said strap, means on the margin of said garment adapted to be engaged by said loop, and a device secured to the garment extending across the loop when engaged with said means.

30 4. In combination, a pair of overalls comprising front and rear portions formed with a downwardly extending side parting therebetween terminating a substantial distance below the waist line, the front portion having 35 an upwardly extending bib thereon, a pair of straps adapted to pass over the shoulders of a wearer for supporting the overalls attached at their rear ends to said rear portion, and at their forward portions to said bib, one 40 only of the forward ends of said straps provided with an extension passing downward below the upper end of said bib and secured to the rear portion adjacent the side parting.

GEORGE H. FRANCISCO.
